SYLVANIA.

INSULATOR-SUPPORT.

1,202,418.

Specification of Letters Patent.

Patented Oct. 24, 1916.

Application filed May 4, 1914. Serial No. 836,118.

To all whom it may concern:

Be it known that I, CHARLES L. PEIRCE, Jr., a citizen of the United States, and a resident of Pittsburgh, in the county of Allegheny and State of Pennsylvania, have invented certain new and useful Improvements in Insulator-Supports, of which the following is a specification.

My invention relates to insulator supports and particularly to improved insulator supporting pins.

Where insulator supporting pins are subjected to heavy strains they tend to give or bend at some point between the cross arm and the insulator supporting end. Where the pins are of wood or solid metal the section between the cross arm and insulator supporting end must therefore be made much heavier. Metal pins for heavy work are therefore very heavy, which of course, involves greater cost of material, and greater expense in the manufacture, handling and shipping thereof. Such solid pins are usually secured to a cross arm or other support by extending their shanks through vertical holes in the arm or support, this bringing the plane of vertical strain and downward pressure on the insulators outside of the supporting plane of the cross arm on the pole. In other words, the plane of the service weight on the pins is not coincident with the plane of support of the cross arm on the pole.

The general purpose of my invention is therefore to overcome all the above objections and among the important objects of the invention are to produce a pin bent up from a length of stock metal bar into such shape that the strength of the resulting pin at any section is proportionate to the strain to which that section will be subjected when in service; to produce such shape and form that the pin can be readily secured in position against the inner face of a cross arm in order to bring the vertical service pressure on the pins in the vertical supporting plane of the cross arm on the pole; to provide improved formation at the upper end of the pin which will adapt it better for receiving an insulator or an insulator receiving thimble; and to produce a pin which is particularly adaptable for use in connection with metallic cross-arms or other structures.

The various features of the invention will

be clearly understood by reference to the accompanying drawings in which—

Figure 1 is a front elevational view of a pin and a portion of a support on which the pin is mounted, and showing also a thimble, partly in section, applied to the upper end of the pin, and Fig. 2 is a side elevational view of the pin and its support.

The pin shown is formed up from a length of channel bar, although commercial bar of other cross section may be used. A suitable length of the bar is bent at 5 mid-way its ends to bring the two halves thereof toward each other into parallelism. The lower sections *a* and *b* of the halves, are not brought together but are left separated to leave a longitudinal slot *c* between them. The halves are further bent at *d* and *e* to bring the sections *f* and *g* above the slot against each other. As the bar is bent with the flanges 6 and 7 on the outside the webs of sections *f* and *g* will be brought back to back so that the resulting section will be of I-beam form. After thus bending the bar the sections *f* and *g* are securely fastened together by upper and lower rivets 8 and 9. The slot *c* is of sufficient width for each pin to receive bolts or fastening means of necessary size to secure the pin to the support. In the drawings the pin is shown secured to a metallic cross arm 10 in the form of an angle bar, and a strap 11 is provided for securing the pin to the arm, the strap ends terminating in threaded studs 12 and 13 for passing through the upper and lower ends respectively of the slot *c*, nuts 14 and 15 engaging the studs and clamping the pin securely to the cross arm. The pin could as readily be secured to a wooden cross arm, in which case a strap could be used or separate bolts passing through the cross arm could be used, or lag screws could be used. This manner of securing the pin admits of adjustability of the pin along the arm, this being impossible with the ordinary form of pin which is inserted in a hole formed in the cross arm when it is made. The securing of the pin in the above manner against the back face of the cross arm has also the decided advantage that the vertical strain or pressure on the pin during service will be in a vertical plane substantially coincident with the plane of support of the cross arm on a pole. These cross arms are usually bolted against the face of the

5 pole or are set into gains cut in the pole. In the ordinary construction where pins are applied in vertical holes in the cross arms, the weight on the pins is in a plane off-set laterally from the plane of support of the pole, that is, the pressure is in a plane outside of the gain and under heavy pressure the cross arm could twist. Where straps are used in connection with a wooden cross arm the arm 10 is strengthened by the strap. Where the ordinary pins are used the arm is in the first place weakened by the pin holes, and when the pins are in place and pull exerted thereon the arms tend to split. I further 15 strengthen the upper end of the pin and adapt it for receiving an insulator or an insulator supporting thimble by welding together the ends and forging them to form a cylindrical neck 16 and a conical shoulder 20 section 17 at the base of the neck. The upper rivet 8 holds the ends together securely preparatory to the welding operation. During the forging operation the flange sections *h* and *i* of the sections *f* and *g* are 25 curled inwardly and the webs are worked until the conical shoulder section 17 results. This shoulder section can be made very smooth and regular to adapt it particularly for intimate reception of the conical skirt *j* 30 of an insulator thimble 18, the neck 16 being threaded to fit the interior thread of the thimble. The end could of course be welded and forged, and then threaded or otherwise treated to adapt it for receiving other forms 35 of insulator supports, as for example a thimble in the form of a wire helix.

In a pin formed up as described, the metal is distributed in accordance with the strains to which the pin will be subjected. Ample 40 metal is provided at the shoulder 17 to resist strains and bending at this point, and the bends *d* and *e* just above the cross arm are gradual and make the pin very strong at this point. The sections *f* and *g* when 45 secured together by the rivets will give great strength. The sections *a* and *b* being separated by the gap *c* will afford ample seating base for the pin against its supporting arm.

In short, a minimum amount of metal is distributed to give maximum strength and 50 efficiency, and the pin has greater strength with less weight than an ordinary cylindrical metal pin intended for the same service. The cost of manufacture and the expense of handling and shipping my improved pin is 55 considerably reduced.

I do not desire to be limited to the exact structure and arrangement shown as changes are no doubt possible which would still come within the scope of the claims.

I claim as follows:

1. An integral metal insulator pin comprising two side members joined at their lower ends and spread apart for a distance upwardly to form flat vertical seating surfaces and to leave a passageway for bolts for securing the pin with one of said flat seating surfaces against a support, the intermediate sections of said side members being rigidly secured together and the upper ends of said 65 side members being welded into a solid cylindrical neck threaded to receive insulators or insulator supporting thimbles.

2. An integral metal insulator pin comprising two side members joined at their 75 lower ends and spread apart for a distance upwardly to form flat vertical seating surfaces and to leave a passageway for bolts for securing the pin with one of said flat seating surfaces against a support, the intermediate 80 sections of said side members being rigidly secured together and the upper ends of said side members being welded into a solid cylindrical neck threaded to receive insulators or insulator supporting thimbles, and a long 85 conical shoulder between said neck and intermediate sections for intimately receiving the skirt of insulators or insulator supporting thimbles.

In witness whereof, I hereunto subscribe 90 my name this 27 day of April, A. D., 1914.

CHARLES L. PEIRCE, JR.
